UNITED STATES PATENT OFFICE.

HENRY B. SAUERMAN, OF CHICAGO, ILLINOIS.

SCRAPER.

1,087,324.

Specification of Letters Patent. Patented Feb. 17, 1914.

Application filed January 27, 1913. Serial No. 744,358.

To all whom it may concern:

Be it known that I, HENRY B. SAUERMAN, a citizen of the United States, residing at Chicago, in the county of Cook and State of Illinois, have invented certain new and useful Improvements in Scrapers, of which the following is a specification.

This invention relates to a device for removing material from one place and depositing it in another, or for making cuts, fills and the like.

The principal object of the invention is to provide new and improved apparatus by means of which the desired result may be accomplished in a more rapid and efficient manner.

A further object of the invention is to provide a new and improved form of scraper bucket which is particularly adapted to be moved to and fro over a surface to be scraped, and which, when so moved, will engage the surface to be scraped in one direction of movement and will slide easily over the surface in the other direction of movement.

A further object of the invention is to provide a new and improved form of scraper bucket which may be readily adapted for use with materials of different characters, by adjusting the depth of cut of the scraper blade, and for producing a simple and strong device of this class which is effective and efficient in operation.

For the attainment of these ends and the accomplishment of other new and useful objects, as will appear, the invention consists in the features of novelty in the construction, combination, and arrangement of the several parts generally shown in the accompanying drawings and described in the specification, but more particularly pointed out in the appended claims.

In the drawings:—Figure 1 is a representation of a scraper of the class described adapted to be moved forward and back over the surface to be scraped for making a fill in a depression. Fig. 2 is a side elevation of a scraper bucket of the preferred form of construction with the scraper blade in raised position for forward movement thereof. Fig. 3 is a side elevation of the same with the scraper blade in position for the rearward movement of the bucket. Fig. 4 is a plan view of the bucket. Fig. 5 is a sectional view taken on the line 5—5 of Fig. 4. Fig. 6 is a view of the bucket adapted for

use without the automatic elevating connection for the scraper blade.

The success of a great amount of construction work is dependent upon the rapidity with which material can be removed from a certain place or with which a fill can be made. The present invention presents a construction in which a scraper bucket can be moved rapidly to and fro over a surface to be scraped without necessitating frequent turnings as is common with horse-drawn buckets and the like, and also with the minimum of resistance for the backward movement of the scraper bucket.

The preferred method of use of this device is illustrated diagrammatically by Fig. 1, in which a scraper bucket designated generally by the reference numeral 10 is drawn to and fro over a surface 11 by means of flexible cables 12 which pass over pulleys 13 and 14 disposed beyond the extremities of the desired length of travel of the scraper bucket and moved by means of an engine 15 having driving connection with the cables 12 and adapted to make a fill in the depression 16.

In construction the scraper bucket preferably comprises side plates 17 spaced apart at their forward end by means of a strip 18 secured to the forward edges thereof and extending above the plates to space them apart, and a plate 19 secured to the rear end of the side plates 17 and secured thereto by means of the angle braces 20. An inside bracing strip 21 and an outer bracing strip 22 are preferably secured to the edge of the plates 17 at the lower edge thereof, the outside strips 22 preferably projecting beyond the rear of the bucket or scraper receptacle and provided with perforations in the projecting portion, and also secured to the outside lower edge of the receptacle and extending rearwardly therefrom are perforated strips 23 slightly spaced from the sides of the receptacle by means of blocks 24, the perforations in these strips 23 and the side strips 22 registering with each other. Extending over the plates 17 at the rear end thereof is a strip 25 upon which is mounted a pulley 26 of any desired or suitable construction.

A scraper blade is pivotally mounted in the rearward extension of the strips 22 and 23. This blade may be of any desired or suitable construction but preferably consists of a plurality of strips 27 curved at their

rearward end, to the bottom of which the runners 28 are connected, and also curved slightly at their rearward end. Connecting the several strips 27 is a rear plate 29, a 5 forward cutting plate 30 and a plate 31 bent upwardly at the ends, the ends being adapted to be inserted between the rearward extensions of the perforated strips 22 and 23 and having a plurality of perforations 32 10 therein. A pivot pin or bolt 33 is inserted through the perforations in said strips and the upwardly extending ends of the plate 31 to form a pivotal connection for the scraper blade and the plurality of perforations 32 is provided so that the depth of cut of the 15 scraper blade may be varied to accommodate the scraper bucket to different materials.

In order to limit the movement of the scraper blade in an upward direction with 20 respect to the scraper receptacle, and thereby to vary the depth of cut for any fixed position of the blade, an adjustable stop device is provided comprising a slotted bar 34 25 preferably curved at the lower end 35 which is adjustably secured to the rear plate 19 of the receptacle by means of a fastening device 36. When the scraper receptacle is drawn in a forward direction the scraper blade will contact with the lower extremity 30 35 of the stop 34, limiting the movement of the blade in that direction and varying the depth of cut thereof to a predetermined extent.

In order to draw the scraper receptacle to 35 and fro it is provided at its forward end, with fastening device 37 preferably consisting of U hooks connected through the strips 18 at a slight distance above the lower edge of the plates 17 to which a chain or flexible 40 member 38 is connected, and at the rear with fastening device 39 preferably secured at the sides of the rear plate 29 to which flexible members 40 are connected. Also 45 connected to the scraper blade, preferably at the center thereof and at the rear extremity, is a flexible member or chain 41 connected to the flexible member 38 which extends upwardly over the pulley 26 and has a claw hook 42 at its free end by means of which 50 the pulling length of the chain may be varied. Connected to the forward chain 38 and the chain 41 is one end of a flexible cable 12, previously referred to, while connected to the chains 40 at the rear of the 55 scraper blade is the end of another cable 12. It is obvious, therefore, that the movement of the cables 12 in both directions will cause a corresponding movement of the scraper bucket as previously set forth. It will also be 60 noted that the flexible member 38, which is connected to the forward end of the receptacle, and the flexible member 41, which is connected to the rear of the scraper blade, are so disposed with respect to each other 65 that the flexible member 41 must be drawn

tight, as shown in Fig. 2, during the forward movement of the receptacle before the flexible member 38 will be drawn tight. In other words, the scraper blade will be elevated in the position shown before the receptacle 70 will be drawn forwardly. In the other direction of movement, as shown by Fig. 3, the scraper blade will be drawn rearwardly so that the rear end of the scraper receptacle will rest upon the runners 28, and the forward flexible member 38 will be slack. 75

It is obvious that instead of having a flexible cable 12 extending over two pulleys, a device may be provided at each end of travel of the bucket for moving it in the corresponding direction. 80

If desired, the flexible member 41 may be dispensed with, in which case a construction, as illustrated by Fig. 6, may be employed. The pulley 26 is dispensed with and a flexible member 41' 85 forms connection between the rear of the scraper blade and the hook 26'. The stop device 34 may be omitted also, if desired.

What I claim is:

1. In a scraper bucket of the class described, the combination with a receptacle, of a scraper blade pivotally connected intermediate its ends at the rear of the receptacle with the cutting edge of the blade extending below the bottom of the receptacle at the rear, and an adjustable stop secured to the receptacle adapted to engage the scraper blade for predetermining the extent of rotation and the inclination of the blade and the depth of cut to be made thereby. 90
2. In a scraper bucket, the combination with a scraper receptacle of a scraper blade pivotally connected thereto at the rear of the receptacle, and runners on the bottom of the blade curved upwardly at the rear thereof whereby the bucket may be drawn rearwardly upon the said runners. 100
3. A scraper bucket of the class described comprising a scraper receptacle, a scraper blade having lateral projections at the ends thereof with a plurality of perforations in each projection, means for pivotally connecting the blade to the receptacle at the lower rear extremity thereof, an adjustable stop secured to the rear of the receptacle and adapted to engage the scraper blade to limit the upward movement of the same about its point of pivotal connection whereby the depth of cut of the blade is varied, and runners on the bottom of the blade curved at the rear thereof upon which the bucket is adapted to rest when it is drawn rearwardly. 110
4. A scraper bucket of the class described comprising a scraper receptacle consisting of side plates, reinforcing strips at the lower and front edges, the strip at the front edges being bent over at the ends and secured to both of the plates to space them apart, a 120
- 125
- 130

plate secured to the rear of the two side plates and additional plates secured to the sides of the receptacle at the rear thereof projecting rearwardly and having perforations in the rearward projections, and a scraper blade pivotally mounted to the perforations in said projections.

5. In a scraper of the class described, a scraper bucket having a pivotally mounted 10 scraper blade, said scraper blade comprising a plurality of separate members curved at their ends, a rear plate connecting the said members, and a removable scraper blade at the forward end of said members.

15. 6. In a scraper of the class described, a scraper bucket having a pivotally mounted scraper blade, said scraper blade comprising a plurality of members spaced apart and curved at their rearward end, runners 20 secured thereto and extending beyond the members at the forward end, a rear blade connecting the ends of said members together, a cutter blade disposed at the forward end of said members and connected to 25 the runners, and a strip connected to said members and upturned at the ends with a plurality of perforations in each end spaced apart in a direction longitudinal of the members.

30. 7. In a scraper of the class described, the combination with a scraper receptacle of a pivotally mounted scraper blade connected thereto, runners on the bottom of the blade, and means to draw the receptacle back and 35 forth over the surface to be scraped, the blade being moved into scraping position in one direction of movement and the receptacle being adapted to slide on the runners in the other direction of movement.

40. 8. In a scraper of the class described, the combination with a scraper receptacle of a scraper blade pivotally connected thereto at one end only, and means for drawing the bucket to and fro over the surfaces to be 45 scraped and for automatically rotating the blade at its pivotal support in accordance with the direction of movement of the receptacle, the blade being operative as a scraper blade in one direction of movement 50 only and as a runner in the other direction.

9. In a scraper of the class described, the combination with a scraper receptacle of a pivotally mounted scraper blade at the rear of the receptacle, an adjustable stop to engage the blade in one direction of movement, and means to draw the receptacle to and fro over the surface to be scraped and for 55 rotating the blade against the stop into a cutting position in one direction of movement only of the receptacle.

10. In a scraper of the class described, the combination with a scraper receptacle, of

a scraper blade pivotally mounted at the rear thereof, a flexible member connected to the free end of the scraper blade and extending over the receptacle, and means connected to the front of the receptacle and to the flexible member, and to the blade from the rear thereof and adapted to move the receptacle in both directions, the blade being 65 moved into cutting position during the forward direction of movement.

11. In a scraper of the class described, the combination with a scraper receptacle having a pulley mounted on top at the rear thereof, an adjustable scraper blade pivotally mounted at the rear and adjacent the bottom of the receptacle extending rearwardly thereof, an adjustable stop connected to the rear of the receptacle and adapted 70 to engage the blade in one direction of movement, runners mounted on the bottom of the blade, a flexible member connected to the rearwardly extending end of the blade and passing over said pulley, a flexible member 75 connected to the front of the scraper receptacle and to the free end of the other flexible member, and means to engage the two flexible members and the rear of the cutter blade to move the receptacle to and fro over the surface to be scraped, the cutter blade being rotated in a position to engage the adjustable stop during the forward movement thereof and being rotated 80 in the opposite direction during the backward movement of the receptacle, whereby 85 the rear end of the receptacle will be supported upon the said runners.

12. In a scraper of the class described, the combination with a scraper bucket of a 100 scraper blade pivotally connected thereto, a flexible member connected to the forward end of the scraper receptacle, another flexible member connected to the rear of the scraper blade and adjustable to engage the free end 105 of the other flexible member, an adjustable stop to engage the scraper blade to vary the scraping depth thereof, and means to engage the connected ends of the two flexible members and the rear of the scraper blade to 110 draw the receptacle to and fro over the surface to be scraped and to rotate the scraper blade about its pivotal support in accordance with the forward and back movement of the scraper.

In testimony whereof I have signed my name to this specification, in the presence of two subscribing witnesses, on this 22nd day of January A. D. 1913.

HENRY B. SAUERMAN.
